UNITED STATES PATENT OFFICE.

NEWTON WHITESEL AND FRED WHITESEL, OF WATERTOWN, NEBRASKA.

WIRE-STRETCHER.

1,152,583.

Specification of Letters Patent.

Patented Sept. 7, 1915.

Application filed October 14, 1914. Serial No. 866,643.

To all whom it may concern:

Be it known that we, NEWTON WHITESEL and FRED WHITESEL, citizens of the United States, residing at Watertown, in the county 5 of Buffalo and State of Nebraska, have invented certain new and useful Improvements in Wire-Stretchers, of which the following is a specification, reference being had to the accompanying drawings.

10 This invention relates to wire stretchers, and particularly to improvements in the wire stretcher covered by our prior Patent, No. 1,110,473, issued September 15, 1914.

An object of this invention is to simplify 15 the construction and arrangement of the parts of the wire stretcher as disclosed in our prior patent, to render the tool more cheaply manufactured, and to increase the usefulness of the same.

20 A further object of the invention is to improve and simplify the anchoring means for supporting the stretcher on a fence post, the means for stretching the wire and the means for clamping the tool to the post 25 being carried by the same member of the device.

With these and other objects in view, as will become more fully apparent as the description proceeds, our invention consists 30 in the novel construction, combination, and arrangement of parts, to be hereinafter more fully described, claimed, and illustrated in the accompanying drawing, in which—

Figure 1 is a top plan view of our improved wire stretcher; Fig. 2 is a side elevational view thereof; Fig. 3 is a bottom plan view with the chain removed; Fig. 4 is a detail sectional view of the head showing the dog mounted therein; and Fig. 5 40 is a detail sectional view of the head taken at right angles with that shown in Fig. 4.

Referring more particularly to the drawing, the wire stretcher includes a post clamp or anchoring member which comprises a 45 head 1 from which projects a pair of arms 2 and 3 which are of the same length and which extend in parallel relation with each other, the arms being held spaced apart by a brace 4. Projecting from the head 1 at 50 right angles to the arms 2 and 3 are another pair of arms 5 and 6, the arms being disposed in parallel relation with each other, and the arm 6 being of relatively greater length than the arm 5. The inner edges of 55 the arms 5 and 6 are provided with spurs 7 which are adapted to engage into the post

to hold the head rigid with relation thereto, and to prevent turning or slipping of the head. The arms 2 and 3 are provided intermediate of their ends with rearwardly 60 projecting ears 8, and disposed between the ears is a grooved sheave 9, having integral therewith a ratchet segment 10. The sheave 9 is rigidly mounted on a shaft 11 which is rotatably mounted at its ends in the ears 8 65 and loosely mounted on the shaft 11 between the ratchet segment and one of the ears 8 is the forward end of an operating lever 12.

The outer edge of the arm 6 is provided 70 with a plurality of inwardly extending slots or recesses 14, and connected to the periphery of the sheave 9 is one end of a post clamping chain 15, one of the links adjacent the outer end of the chain being adapted 75 for engagement within one of the slots 14 in the arms, whereby the stretcher may be connected to posts of various sizes and to rotate the sheave 9 whereby the chain 15 may be tightened about the post, a lug 16 80 projects laterally from the segment 10 at one end thereof. As shown in the drawing, the lug 16 is disposed in the path of the lever 12, whereby when the lever is swung in the proper direction, it is engaged against 85 the lug 16 and the sheave 9 is rotated to tighten the chain about the post. To prevent rotation of the sheave in the reverse direction, a pawl 17 is pivotally connected 90 to the arm 2, the pawl being normally engaged against the periphery of the ratchet segment 10.

The head 1 is provided with a chamber 18 in which is pivotally mounted a wire holding dog 19, the dog being provided with the 95 usual serrations to bite into the wire which is designated by the letter W, the dog being adapted to bind the wire against the adjacent wall 20 of the head. The outer wall of the chamber is divided to provide a passage 100 way 21 through which the wire may be inserted within the head and against the wall 20. The dog 19 is rigidly mounted on a shaft 22 to one end of which a lever 23 is connected, and projecting from the lever is a pin or stud, to which one end of a coiled spring 24 is connected, the other end of the spring being connected to a pin or stud 105 projecting from the arm 2. The connection of the spring with the lever 23 is such that 110 when the lever is swung to a position to shift the holding dog 19 from operative to

inoperative position, the lever will pass the dead center and thereby cause the spring to operate to hold the dog in an operative position until the lever is again shifted to bring 5 it past the dead center in an opposite direction, whereupon the tension of the spring 24 will cause the dog to grip the wall 20 of the chamber 18.

Formed on the lever 12 adjacent its forward end is a head 25 in which a chamber 26 is provided, a pulling dog 27 being mounted in the chamber on a shaft 28 one end of which projects from the head and carries a lever 29. A spring 30 is connected 10 at one end to the lever 29 and at its other end to the lever 12, the spring 30 operating in the same manner as the spring 24 to cause the lever 29 to hold the pulling dog in an operative relation relative to one wall 15 of the head 25, the outer wall of the head being also divided to provide a passage way 20 31 to permit the insertion of the wire within the head. The post chain 15 is preferably provided with teeth 32 which are adapted to 25 bite into the post to assist in holding the stretcher thereon when the same is in a position for use.

In the practical use of our improved wire stretcher, the arms of the head are brought 30 into engagement with the post, and one of the links on the free end of the chain is engaged in one of the slots 14 in the arm 6, whereupon the lever 12 is rotated to tighten 35 the chain and thus cause the spurs 7 on the arms to sink into the post and anchor the tool in position. The dog 19 is then moved to unlocked position and the wire is passed through the passage way 21 in the chamber 18, and the wire is also passed through the 40 passage way 31 in the chamber 26 with the pulling dog 27 in unlocked position, whereupon the dog 27 is brought into engagement with the wire, so that when the lever is

swung in the proper direction, the wire is placed under the desired tension, and the 45 locking dog 19 is then moved to locked position to securely grip the wire and hold the same until the operator staples the wire to the post.

From the above description taken in connection with the accompanying drawing, it will be seen that an extremely simple fastening means is provided for holding the clamping chain in position, and that the lever 12 serves as a means for tightening the 50 chain, and also for placing the wire under 55 the desired tension.

What we claim is:—

In a wire stretcher, a head provided with pairs of post engaging arms, each arm of 60 one of said pairs being provided with a laterally projecting lug, a shaft rotatably mounted in said lugs, a grooved sheave secured on said shaft, a ratchet segment formed on one side of said sheave and having a lug formed thereon, a chain connected at one end to the sheave and having its other end arranged for engagement with one of the other arms, a lever mounted at one end on said shaft, said lug being disposed in the 65 path of the lever, whereby upon movement of the lever in the proper direction, said sheave will be rotated to tighten said chain, wire holding means carried by the lever, and means carried by the head for preventing 70 rotation of the sheave in the opposite direction to loosen the chain.

In testimony whereof we hereunto affix our signatures in the presence of two witnesses.

NEWTON WHITESEL.
FRED WHITESEL.
